William C. Stewart,

INVENTOR

BY Victor J. Evans

ATTORNEY

WITNESS:

P. J. Hickey

UNITED STATES PATENT OFFICE.

WILLIAM COY STEWART, OF LAMAR, SOUTH CAROLINA.

GATE LATCH.

Application filed August 10, 1925. Serial No. 49,433.

The object of this invention is the provision of a simply constructed cheaply manufactured automatically operated latch for gates, in which the latch bar may be locked to hold the gate closed, and likewise locked to hold the gate in release position.

The drawing which accompanies and which forms part of this application illustrates the improvement, and wherein:—

10 Figure 1 is a plan view of a latch in accordance with this invention.

Figure 2 is an edge view thereof.

15 Figure 3 is a sectional view on the line 3—3 of Figure 1.

Figure 4 is a plan view showing a gate latched by the improvement.

As disclosed by Figure 4 of the drawing, a gate 1 is hingedly connected to a post 2 and is designed to abut, when in closed position, with a strip 3 on an abutment post 4.

20 The fixed element of my improvement comprises a metal bar 5 having its inner end flanged in one direction, as at 6, the said flange being reinforced by a weight 7 arranged between the bar and the said flange. The flange contacts with one face of the abutment post 4 and has passed therethrough securing elements 8. By reference to Figure 4 of the drawing it will be noted that the bar is secured a suitable distance 25 from the strip 3. The bar has its outer end formed with a right angular extension in the nature of an elongated lug 9, the same being directed toward the hinge post 2.

30 The lug 9 is bifurcated to receive therein one end of a latch plate 10. The plate is pivoted in the lug as indicated by the numeral 11, and the lug, to one side of the pivot has its bifurcated portion provided with an opening 12, the purpose of which 35 will be presently apparent.

The latch plate 12 is influenced to outward swinging with respect to the supporting bar 5 through the medium of a spring 13. The 40 spring is sustained between the latch plate and the supporting bar through the medium of a U-shaped bail 14 that has its legs passing through and secured on the bar 5. The opposite end of the bail passes through a slot 15 in the latch plate 10, and passing 45 transversely through this said opening there is a pin 16 providing a guide element for

the bail. Obviously the pin 16 will engage the outer rounded end of the bail 14 and thus limit the outward swinging of the 55 latch plate 10 under the influence of the spring 13.

The normal position of the latch plate is as shown in Figures 1 and 4, and the gate 1 when swung to closed position, will contact with the latch plate to move the same on its pivot against the tension of the spring 13 to permit of the gate being swung closed. The spring, thereafter, will again swing the latch plate to normal gate holding position. 65

When it is desired to hold the latch plate against or in a plane with that of the supporting bar 5, the latch plate is swung toward the bar, and a removable element, such as a pin 17, is passed through the openings 12 in the lug 9 to contact with the inner face of the latch plate. The gate may be easily opened by pressure against the latch plate, and while it is believed that the foregoing description, when taken in connection with the drawing, will fully set forth the simplicity of my construction, I desire it understood that I am not to be restricted to the precise details herein set forth and hold myself entitled to such 70 changes therefrom as fairly fall within the scope of what I claim.

Having described the invention, I claim:—

1. A gate latch comprising a bar having an angle end which is fixed to one side of an abutment post, a reinforcing rib for the flange, said bar having its outer end formed with an angularly disposed bifurcated lug directed toward the hinge post, a latch plate having one end pivoted in said lug, a spring 85 between the bar and latch plate for swinging the latter angularly with respect to the former and in gate contacting position, a bail providing a guide for the spring fixed to the bar and slideable through the latch plate, a pin carried by the latch plate and passing through the bail, said lug having an opening therethrough, and a pin designed to be passed through said opening to contact with one side of the latch plate, when 90 the latter is swung parallel with the bar for holding the latch plate out of gate engaging position. 95

2. A gate latch comprising in combina-

tion, a bar having an attaching flange at one end adapted to be secured to the abutment post for the gate, an offset bifurcated lug projecting from the other end of the bar, a latch plate arranged at one side of said bar and having one end pivoted within said bifurcated lug, a coil spring interposed between the bar and latch plate and normally holding the latter in the path of move-

ment of said gate for the purpose specified, 10 said lug having aligned openings, and a pin adapted to be positioned in said openings to engage and hold the latch plate parallel with said bar and out of the path of movement of said gate.

15 In testimony whereof I affix my signature.

WILLIAM COY STEWART.
